UNITED STATES PATENT OFFICE.

ERNEST J. S. DAVIS, OF KNOXVILLE, IOWA, ASSIGNOR OF ONE-HALF TO
ANDREW VANDRIMMELEN, OF KNOXVILLE, IOWA.

THILL-COUPING.

SPECIFICATION forming part of Letters Patent No. 784,990, dated March 14, 1905.

Application filed June 4, 1904. Serial No. 211,181.

To all whom it may concern:

Be it known that I, ERNEST J. S. DAVIS, a citizen of the United States, residing at Knoxville, in the county of Marion and State of 5 Iowa, have invented new and useful Improvements in Thill-Couplings, of which the following is a specification.

My invention relates to new and useful improvements in thill-couplings; and its object 10 is to provide an attachment of simple and inexpensive construction which is adapted to be placed upon the clip of the coupling and which is provided with means whereby rattling of the thill-iron within the clip is prevented.

15 A further object is to provide means for locking the pin of the coupling in position within the thill-iron.

With the above and other objects in view the invention consists of a frame adapted to 20 be placed outside of and hung from the arms of the clip of the thill-coupling, and this frame has inwardly-extending ends which engage the arms, so as to hold the frame in position thereon. A spring engages one end of the 25 frame and has a curved portion for bearing on the thill-iron, and this spring is adapted to be tensioned by means of a cam which is mounted within the frame and is adapted to be operated by a suitable handle. A pin-retaining 30 strip is pivoted to the frame and is adapted to hold the coupling-pin in position.

The invention also consists of the further 35 novel construction and combination of parts hereinafter more fully described and claimed, and illustrated in the accompanying drawings, showing the preferred form of my invention, and in which—

Figure 1 is a perspective view of a coupling. Fig. 2 is a front elevation of the coupling, the thill-iron being shown in section. Fig. 3 is a horizontal section through the antirattler attachment, and Fig. 4 is a detail view showing the manner of connecting the spring to the frame of the attachment.

45 Referring to the figures by numerals of reference, 1 is an axle having a clip 2 of ordinary construction secured thereon, said clip being provided with forwardly-projecting

arms 3 for the reception of a coupling-pin 4. This coupling-pin extends through a thill-iron 5 of ordinary construction. An attachment is provided for preventing rattling of the parts of the coupling, and this attachment comprises a frame 6, which is substantially rectangular in form and has inwardly-turned ends 55 7, which extend over and bear upon the arms 3. The frame 6 incloses the arms of the clip and has a recess 8 at its lower end, in which is located a tongue 9, which fits within a slot 10, formed within one end of a spring 11. 60 This spring has a curved portion 12, which bears upon the end of the thill-iron 5. A rod 13 is revolvably mounted within the sides of frame 6 and has an extension 14 at one end, which forms a handle. The central portion 65 of the rod 13 is pressed out of alignment with the remainder thereof, as shown at 15, so as to produce a cam which is adapted to press the spring 11 forward and cause the curved portion 12 thereof to tightly bear upon the 70 end of the thill-iron. An ear 16 extends laterally from one side of the frame 6 and serves to support a retaining-plate 17, which is pivoted to said side of the frame, as shown at 18, and is adapted to overlap the head of the 75 coupling-pin 4 and prevent the parts from becoming detached. This retaining-plate 17 has a laterally-extending ear 19, which forms a thumb-piece whereby the strip can be readily moved from position upon the pin-head. 80 By having a space between the ends 7 of the frame 6 said frame can be spread apart or contracted, so as to adapt it for use upon clips of different widths.

When it is desired to attach this antirattler 85 device to a clip, the thill-iron is removed and the frame 6 is placed over and suspended from the arms 3. The thill-iron 5 is then placed between the arms 3, and the coupling-pin 4 is inserted thereinto. The spring 11 is so proportioned that when the parts are in these positions the curved portion 12 of the spring 90 will bear lightly upon the end of the thill-iron. Strip 17 is then swung downward upon the ear 16 and assumes a position upon the 95 head of the pin 4, and thereby prevents it

from being accidentally displaced. After the strip 17 has been swung downward into retaining position the cam 15 is rotated, so as to press the spring 11 tightly against the thill-iron, thereby holding all of the parts securely together and preventing rattling. The extension 14 of the rod 13 does not contact with the bottom of the axle until after the cam 15 has passed the point of greatest pressure on the spring. It will therefore be seen that this cam and the parts connected therewith are held in place by the pressure of the spring thereagainst. Moreover, the inner end of the strip 17 is straight and at right angles to the side edges thereof, and when the spring 11 is tensioned in the manner above described the inner end of the strip 17 is pressed against the flat piece of the axle, and said strip is therefore prevented from being moved either upward or downward. The head of pin 4 projects slightly beyond the arm 3 of the clip, and therefore prevents the arm 6 from slipping forward out of position in the event of the breaking of spring 11. Should the spring become broken, the parts will remain in their proper positions, and the retaining-strip 17 will continue to lock the coupling-pin in place.

In the foregoing description I have shown the preferred form of my invention; but I do not limit myself thereto, as I am aware that modifications may be made therein without departing from the spirit or sacrificing any of the advantages thereof, and I therefore reserve the right to make such changes as fairly fall within the scope of my invention.

Having thus described the invention, what is claimed as new is--

1. An antirattler attachment for couplings comprising a frame having inwardly-bent separable ends and a laterally-extending ear, a retaining-strip pivoted to the frame and adapted to be supported by the ear, a lug upon the frame, a spring having a stationary apertured end detachably engaging the lug, said spring also having a curved portion, and a cam mounted within the frame for tensioning the spring.

2. In a device of the character described, the combination with a clip having arms extending from it; of a thill-iron between the arms, a longitudinally-movable coupling-pin engaging the arms and thill-iron, a frame partly surrounding the arms and suspended therefrom, one end of said frame having inwardly-bent and separable supporting portions bearing upon the arms, an ear upon the frame, a lug integral with one end of the frame, a spring having an apertured stationary end detachably engaging the lug, said spring being adapted to bear upon the thill-iron, means for tensioning the spring and a retaining-strip pivoted to the frame and adapted to extend over one end of the coupling-pin and to bear upon the ear.

In testimony whereof I affix my signature in presence of two witnesses.

ERNEST J. S. DAVIS.
